UNITED STATES PATENT OFFICE

167,631

BRASSIÈRE

Mathias Imershein, New York, N. Y., assignor to Graceform-Camlin Corset Co., Inc., New York,
N. Y., a corporation of New York

Application April 4, 1952, Serial No. 19,193

Term of patent 14 years

(Cl. D20—4)

To all whom it may concern:

Be it known that I, Mathias Imershein, a citizen of the United States of America and resident of the county, city, and State of New York, have invented a new, original, and ornamental Design for a Brassière, of which the following is a specification, reference being had to the accompanying drawing forming a part thereof, and which is a front view of a brassière, embodying my new design.

I claim:

The ornamental design for a brassière, as shown.

MATHIAS IMERSHEIN.
